(57) **CLAIM**

The ornamental design for fuel-air mixer, as shown and described.

DESCRIPTION

FIG. 1 is a top perspective view of a fuel-air mixer, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded perspective view thereof; and,

FIG. 9 is a sectional view thereof, taken along line 9-9 of FIG. 6.
